UNITED STATES PATENT OFFICE.

CHARLES M. STOUP, OF FLAT ROCK, MICHIGAN.

THILL-COUPING.

SPECIFICATION forming part of Letters Patent No. 230,586, dated July 27, 1880.

Application filed May 15, 1880. (No model.)

To all whom it may concern:

Be it known that I, CHARLES M. STOUP, of Flat Rock, in the county of Wayne and State of Michigan, have invented a new and useful improvement in Thill-Couplings, of which the following is a specification.

The nature of my invention relates to an improvement in thill-couplings of that class wherein a latch bolt or spindle is impelled 10 through the bolt-holes of the thill-clip by a spiral spring; and it consists in the novel and peculiar construction and combination of the elongated thill-bolt with a bracket on the quarter-clip, its actuating-spring, and an in- 15 closing-case for the same, as more fully hereinafter set forth.

Figure 1 is a perspective view. Fig. 2 is a longitudinal section.

In the drawings, A represents the axle-arm, 20 with the usual thill-clip *a* and quarter-clip *b*, the latter having a bracket, *b'*, forged on the front end of its bar, with an eye in the axial line of the bolt-holes in the thill-clip.

B is the rear end of the thill, with the iron 25 thill-hook *B'*, behind which a rubber block or "anti-rattler" of vulcanized rubber, *a'*, is inserted between the jaws of the thill-clip.

C is an elongated bolt playing through the

eyes of the clips *a* and *b*. It is formed with three shoulders, *c c' c²*. The shoulder *c²* serves 30 as a stop to limit its movement forward in the thill-clip. The shoulder *c'* serves as a gripe by which it may be retracted, and between the shoulder *c* and the bracket *b'* of the quarter-clip a spiral spring, *d*, is interposed to automatically project the outer end through the 35 eyes of the thill-clip.

The spring is covered and protected by a cylindrical casing, *e*, extending outwardly far enough to conceal it and the shoulder *c*. 40

By this construction and arrangement it is impossible for the thill-bolt to become detached and lost, while for ease and facility of operation it cannot be excelled.

What I claim as my invention is— 45

In combination with the thill-clip *a* and quarter-clip *b*, with its bracket *b'*, constructed as described, the coupling-bolt *C*, provided with shoulders *c c' c²*, actuated by the spring *d* in its case *e*, and playing through the eyes of said 50 clips, substantially as described and shown.

CHARLES M. STOUP.
